TOY SIMULATING A CAMERA

Adelbert J. Jackson, Kalamazoo, Mich.

Application August 16, 1948, Serial No. 44,453

12 Claims. (Cl. 46—175)

1

This invention relates to improvements in a toy simulating a camera.

The main objects of this invention are:

First, to provide a toy simulating a camera which may be manipulated by quite young children and at the same time affords entertainment and amusement for both children and adults.

Second, to provide a toy of this character which may be used as an accessory in playing a game.

Third, to provide a toy simulating a camera which may be very economically produced and at the same time is substantial and durable in as much as the parts are arranged and associated so that they are not injuriously affected even when improperly manipulated.

Further objects relating to details and economies of the invention will appear from the description to follow. The invention is defined in the claims. The drawings, of which there is one sheet, illustrate a preferred embodiment of my invention, in which:

Fig. 1 is a front perspective view of a structure embodying my invention with the shutter element shown in projected position by full lines and a card shown in projected position by dotted lines.

Fig. 2 is a transverse section on a line corresponding to line 2—2 of Fig. 3, a projected card being illustrated in full lines, parts being shown in full lines for convenience in illustration.

Fig. 3 is a vertical section on the line corresponding to line 3—3 of Fig. 2.

Fig. 4 is a plan view of a card with a figure or picture thereon.

Fig. 5 is a rear view of the shutter element.

Fig. 6 is a fragmentary vertical section of a modified form of my invention.

The embodiment of my invention illustrated in the accompanying drawings comprises a box-like body member designated generally by the numeral 1 and comprising a front wall 2, a rear wall 3, side walls 4—4 and a top 5. In the structure illustrated the box is provided with a partition 6 extending between the front and rear walls and providing a compartment 7 adapted as a shutter compartment and as a magazine compartment and also to receive the actuating roller.

The compartment or space 8 in the embodiment illustrated, is utilized to receive a click device. It will be understood that the shutter and the cards might extend from side to side of the box. The cover 5 is provided with downturned supporting end portions 9 which are disposed against the inner sides of the side walls and desirably adhesively secured thereto. They thus constitute reinforcing members for the box and permit the use of quite light stock.

The partition 6 serves also as a support for the shaft 10 which extends through the side

2

walls, the top supporting members 9 and the partition, the shaft being in supported bearing relation to these several parts which are provided with bearing openings 11 and 12 for the shaft. The shaft is provided with finger pieces 13 at its ends. The forward edge of the top 5 is cut away to provide a slot 14 through which the shutter element 15 may be projected as shown in Fig. 1. The rear edge of the top is cut away to provide an opening 16 through which the cards 17 may be introduced into the magazine portion of the compartment 7 or projected as is indicated in Figs. 2 and 3.

The side edges of the shutter 15 are slit and the portions between the slits are turned rearwardly to provide stops 18 which engage the under side of the top when the shutter element is projected, thus limiting its projecting movement.

In the embodiment illustrated, the shutter element is provided with a peep hole 19 and has a simulation 20 of a flash bulb printed or reproduced thereon.

The front wall of the box has a plurality of concentric circles 21 on the outer side thereof surrounding a spot 22 simulating a lens opening, the circles being intended to simulate a lens opening adjusting means. The shaft is provided with a resilient roller 23 which is desirably of quite yieldable rubber so that it may be substantially compressed. This roller is of such diameter that it engages the rear side of the shutter element slidably urging it against the inner side of the front wall and also frictionally engaging it.

A plurality or group of cards 17 are desirably arranged in the magazine portion of the compartment 7 and yieldingly urged forward by a follower member 29 which as illustrated is formed of a card-like piece of material folded upon itself as shown in Fig. 3 to springably engage the rear card of the group and urge the cards forwardly against the roller 23. The roller 23 is compressible to a substantial degree so that a number of cards may be arranged in the magazine and are supported in frictional engagement with the roller, the roller constituting a supporting means for the group of cards and yieldingly urging them rearwardly.

50 When the roller is actuated in one direction, that is, in a clockwise direction as shown in Fig. 3, the shutter element is projected until its stops 18 engage the under side of the cover. When the roller is operated in the reverse or counter-clockwise direction the shutter element is retracted and a card projected for convenient grasping.

In the embodiment illustrated, I provide a click device designed to imitate the click or snap of a shutter and this comprises a spring 24 secured at 55 25 on the under side of the top. A push button 26 having a head or flange at its inner end is sup-

ported by a spring in a hole provided therefor in the top. When this push button is pushed downwardly and released the spring returns it with a snap or spring action so that its head 27 strikes the under side of the top and simulates the click or sound of a shutter. The cards bear legends or pictures or both. Where legends are used, the cards are designed for the playing of a game, for example the individual whose picture has presumably been taken must pay the forfeit indicated on the card.

In the embodiment shown in Fig. 6 the resilient follower member 29 is omitted and the thumb or finger hole 28 provided in the rear wall 2 so that the cards may be pressed forwardly by the operator.

The toy of my invention may be very economically produced and it affords entertainment and amusement for various ages, although primarily intended for entertainment and amusement of children.

Having thus described my invention, what I claim as new and desire to secure by Letters Patent is:

1. A toy simulating a camera, comprising a box including a front wall, a rear wall, and side walls, a partition extending from front to rear thereof in spaced relation to said side walls providing a simulated shutter element and card magazine compartment, a top member having down turned end portions disposed on the inner sides of said side walls in supporting relation thereto, the front edge of the top member being cut away to provide a slot through which a simulated shutter element may be projected, and a rear portion of the top member being cut away to provide an opening through which cards may be introduced and discharged from said compartment, a shaft disposed through and supported by said side walls, partition and top member end portions, a resilient roller on said shaft, a simulated shutter element disposed on the inner side of said front wall and having rearwardly turned stops at its side edges engageable with said top member to limit its projection through said slot, said shutter element being supportingly engaged and urged against said front wall by said roller, said roller being in supporting engagement with the front card of a group disposed at the rear of said roller whereby actuation of the roller in one direction acts to project the shutter element and actuation in the other direction acts to retract the shutter element and acts to project the front card of the group.

2. A toy simulating a camera, comprising a box including a front wall, a rear wall, and side walls, providing a simulated shutter element and card magazine compartment, a top member, the front edge of the top member being cut away to provide a slot through which a simulated shutter element may be projected, and a rear portion of the top member being cut away to provide an opening through which cards may be introduced and discharged from said compartment, a shaft disposed through and supported by said side walls, a resilient roller on said shaft, a simulated shutter element disposed on the inner side of said front wall and having rearwardly turned stops at its side edges engageable with said top member to limit its projection through said slot, said shutter element being supportingly engaged and urged against said front wall by said roller, said roller being in supporting engagement with the front card of a group disposed at the rear of said roller whereby actuation of the roller in one

direction acts to project the shutter element and actuation in the other direction acts to retract the shutter element and acts to project the front card of the group.

3. A toy simulating a camera comprising a box including a front wall, a rear wall, and side walls, a top member, there being a slot at the front edge of said top member through which a simulated shutter element may be projected and an opening 10 at the rear thereof through which cards may be introduced and discharged, a shaft disposed through and supported by said side walls, a resilient roller on said shaft, a simulated shutter element disposed on the inner side of said front 15 wall and having rearwardly turned stops at its side edges engageable with said top member to limit its projection through said slot, said shutter element being supportingly engaged and urged against said front wall by said roller, said roller 20 being in supporting engagement with the front card of a group disposed at the rear of said roller, means for yieldingly urging the front card of the group against said roller whereby actuation of the roller in one direction acts to project the shutter 25 element and actuation in the other direction acts to retract the shutter element and acts to project the front card of the group.

4. A toy simulating a camera comprising a box including a front wall, a rear wall, and side walls, 30 a top member, there being a slot at the front edge of said top member through which a simulated shutter element may be projected and an opening at the rear thereof through which cards may be introduced and discharged, a shaft disposed 35 through and supported by said side walls, a resilient roller on said shaft, a simulated shutter element disposed on the inner side of said front wall and having rearwardly turned stops at its side edges engageable with said top member to 40 limit its projection through said slot, said shutter element being supportingly engaged and urged against said front wall by said roller, said roller being in supporting engagement with the front card of a group disposed at the rear of said roller, 45 whereby actuation of the roller in one direction acts to project the shutter element and actuation in the other direction acts to retract the shutter element and acts to project the front card of the group.

5. A toy simulating a camera, comprising a box including a front wall having a simulated lens thereon, a rear wall, side walls, and a top, the top coacting with the front wall to provide a simulated shutter element slot and with the rear 55 wall to provide a card magazine opening, a shaft disposed horizontally through the side walls of said box and provided with a finger piece, a simulated shutter element slidably disposed on the inner side of the front wall and projectable 60 through said shutter element slot, a roller on said shaft yieldably and frictionally engaging said shutter element to supportingly urge it against the front wall and to project the shutter element when the roller is rotated in one direction, said 65 roller being adapted to yieldably engage the front card of the group arranged in said box, and project it when the shutter element is retracted.

6. A toy simulating a camera, comprising a covered box having a shutter opening through 70 which a simulated shutter element may be projected, and an opening through which a card may be projected, said box being adapted to receive a group of cards, a simulated shutter element slidably disposed within said box and projectable through said shutter opening, stops on

said shutter engageable with said box for limiting the projection of said shutter element, a manually actuated shaft mounted in said box parallel to and between said openings, and a roller of substantially yieldable material mounted on said shaft within said box in frictional engagement with the shutter element and in yielding engagement with the front card of a group of cards arranged within the box, whereby rotation of the roller in one direction projects the shutter element and rotation in the opposite direction retracts the shutter element and projects a card.

7. A toy simulating a camera comprising a box including front, rear and side walls, said front wall having a simulated lens reproduced on the outer side thereof, and a top having its front edge spaced from the front wall to provide a slot and from the rear wall to provide a card magazine opening, a vertically slidable flat element having simulated exterior elements of a camera reproduced thereon reciprocatingly supported by said front wall and projectable through said slot, a yieldable card follower supported by the rear wall, a spindle journaled on said side walls and provided with a finger piece at one end and with a sponge rubber roller in supporting frictional engagement with said flat element, and adapted for yieldable frictional engagement with the front card of a group disposed between said roller and said follower within the magazine portion of the box, whereby rotation of the roller in one direction projects the flat element and rotation in the opposite direction retracts the flat element and projects the front card in the group, and a noise making fixture mounted within said box and having a manually operative portion projecting therefrom for actuation to simulate the sound of a shutter.

8. A toy simulating a camera comprising a box including front, rear and side walls, said front wall having a simulated lens reproduced on the outer side thereof, and a top having its front edge spaced from the front wall to provide a slot and from the rear wall to provide a card magazine opening, a vertically slidable flat element having simulated exterior elements of a camera reproduced thereon reciprocatingly supported by said front wall and projectable through said slot, a yieldable card follower supported by the rear wall, a spindle journaled on said side walls and provided with a resilient roller in supporting frictional engagement with said flat element, and adapted for yieldable frictional engagement with the front card of a group disposed between said roller and said follower within the magazine portion of the box, whereby rotation of the roller in one direction projects the flat element and rotation in the opposite direction retracts the flat element and projects the front card in the group, and a noise making fixture mounted within said box and having a manually operative portion projecting therefrom for actuation to simulate the sound of a shutter.

9. A toy simulating a camera, comprising a box including a front, rear and side walls and having a top opening through which a card may be projected, said front wall having a simulated lens structure reproduced on the outer side thereof, said box having space to receive a group of photograph simulating cards, a flat element having simulated exterior elements of a camera reproduced thereon disposed within said box in spaced relation to said card space and projectable through an opening in the top thereof, an actuating roller of resilient material disposed between

65

said card space and said flat element for projecting and retracting the flat element and projecting a card, manual means for rotating said roller, said roller being in frictional engagement with the flat element and adapted to frictionally engage a card from said group of cards, the rear wall of the box having a finger opening therein through which the card may be pressed against the roller.

10. A toy simulating a camera, comprising a box including a front, rear and side walls and having a top opening through which a card may be projected, said front wall having a simulated lens structure reproduced on the outer side thereof, said box having space to receive a group of photograph simulating cards, a simulated shutter element having simulated exterior elements of a camera reproduced thereon disposed within said box and projectable through an opening in the top thereof, means for projecting and retracting said shutter element and a card from said group, said means including an actuating roller of resilient material disposed in said box, manual means for rotating said roller, said roller being in frictional engagement with a card to be projected.

11. A toy simulating a camera, comprising, a covered box having an opening through which a flat element may be projected and a parallel opening through which a card may be projected, 30 said box having space to receive a group of cards below said second opening, a flat element having simulated external elements of a camera reproduced thereon slidably disposed within said box and projectable through said first opening, a 35 manually actuated shaft mounted in said box parallel to and between said openings and a roller of substantially yieldable material mounted on said shaft within said box in frictional engagement with said flat element and positioned to 40 yieldably engage the front card of a group of cards arranged within said space whereby rotation of the roller in one direction projects the flat element and rotation in the opposite direction retracts the flat element and projects a card, and 45 a noise making device mounted in said box and having a manually operative control projecting therefrom for actuation to simulate the noise of a shutter.

12. A toy simulating a camera comprising, a box including a front, rear and side walls and having a top opening through which a card may be projected, said front wall having a simulated lens structure reproduced on the outer side thereof, said box having space to receive a group of photograph simulating cards, an extensible element disposed within said box and projectable through an opening in the top thereof, said element having indicia reproduced thereon simulating an external auxiliary part of a camera and visible when said element is projected, an actuating roller of resilient material disposed in said box and frictionally engaging said element for projecting and retracting the same, and manual means for rotating said roller.
